UNITED STATES PATENT OFFICE.

ROBERT ESPIE, OF MOUNT CARROLL, ILLINOIS.

GOVERNOR.

1,410,742.

Specification of Letters Patent. Patented Mar. 28, 1922.

Application filed October 16, 1919. Serial No. 331,008.

To all whom it may concern:

Be it known that I, ROBERT ESPIE, a citizen of the United States, and a resident of Mount Carroll, in the county of Carroll and 5 State of Illinois, have invented a new and Improved Governor, of which the following is a full, clear, and exact description.

This invention relates in general to governors, and particularly to an improved governor for marine engines for automatically actuating a throttle of the engine when the propeller rises and ceases to impart the normal propulsion to the shaft.

The primary object of the invention is to 15 provide a governing device for automatically throttling the engine when the propeller is raised out of the water and thus permitted to race, due to the vessel being abnormally rocked by a heavy sea.

20 The illustrative embodiment of the invention is shown on the accompanying drawing, and in which Figure 1 is a top plan view illustrating the application of the invention to a marine propeller shaft, and Figure 2 is a side elevation partly in section.

Referring to the drawings by reference characters the propeller shaft A will be considered as of a conventional type with the exception that it is divided into two sections, 30 one of which namely, that on which the propeller B is mounted, is capable of longitudinal movement relative to the other section, but so connected to the other section that at no time is one section free to rotate without 35 imparting rotation to the other section. This is accomplished by means of the two-part coupling 5, each part of which being provided with a multiplicity of relatively long fingers or teeth 6 with slots between 40 the teeth or fingers so that the fingers on one part may be received by the slots in the other part and vice versa. For convenience that section of the propeller shaft between the coupling 5 and the propeller B will be 45 referred to as a driven section, whereas the other part will be referred to as a driving section.

In actual practice the driven section of the shaft will extend through a stuffing box in 50 the hull of the vessel, however, this stuffing box is not shown in the present illustration, but in its stead the shaft is shown as extended through a wall 7, the opening through the wall made to receive the shaft

acting in the capacity, at least for illustrat- 55 ing purposes, as a bearing. Supported by the standard 8 is a permanently fixed block 9 having an axial opening through which the driven section of the shaft passes with freedom of rotation. The block is braced at its 60 top by means of a bracket 10 which extends substantially parallel with the shaft and terminates with its end fastened to the wall 7. Slidably mounted on the driven section of the shaft and diametrically spaced from the 65 block 9 is a second block 11. This block is so positioned relative to block 9 as to support one end of a tension device which is interposed between the confronting faces of 70 the blocks. This tension device in its preferred form comprises a plurality of coil springs 12. The normal tendency of these springs is to impart a longitudinal movement to the driven section of the shaft, the direction of the movement being away from 75 the driving section. Now inasmuch as an abutment 13 is fixed to the driven section of the shaft behind the slidably mounted block 11, expansion of the springs will slide the block 11 away from the block 9 and until it 80 abuts against the abutment 13, whereupon the continued expansion of the springs will slide the driven section of the shaft away from the driving section and partially disengage the teeth in the two-part coupling 5. 85 The disengagement of the coupling must never be complete as it is necessary to always maintain the driving section in driving relation with the driven section, therefore to prevent complete disengagement of the sections at the coupling a stop 14 is fixed to the 90 driven section of the shaft behind the abutment 13 and the stop being so positioned as to leave a space between it and the wall 7, substantially that of the length of the teeth 95 or fingers 6. Inasmuch as the abutment 13 is fixed to and must rotate with the driven section of the shaft and as the block 11 contacts therewith friction reducing means such as the balls 15 working in annular grooves 100 in both the faces of the abutment and block, are provided to permit rotation of the abutment relative to the block 11 with a minimum frictional engagement. Fixed to the block 11 as at 16 is an arm 17 which extends 105 vertically of the block and pivoted to the bracket 10 as at 18. Fastened to the end of this arm is a connection 19 which connects

with the throttle of the engine which furnishes the necessary power to the propeller shaft.

The operation of the device is substantially as follows:

So long as the propeller is properly submerged the resistance of the water incident to the rotation of the propeller will impart a thrust to the driven section of the shaft in 10 a direction to maintain the two parts of the coupling 5 intact. However, should the vessel be pitched at an abnormal angle which would cause the propeller to be raised from the water and the resistance of the water 15 removed, the propeller will race. At the same time the thrust on the driven section of the shaft is relieved permitting the tension device, or rather the springs 12 to expand and impart a longitudinal movement 20 to the driven section of the shaft. This will bring about a sliding movement of the block 11 whereupon the arm 17 will be rocked about its pivot and the connection 19 to the throttle valve manipulated in a 25 manner to control the effective port area of the throttle valve and reduce the speed of the engine, likewise the speed of the propeller shaft.

Having thus described my invention, what 30 I claim as new and desire to secure by Letters Patent is as follows:

1. The combination of a propeller shaft divided by a coupling capable of permitting longitudinal movement of one of the sections 35 of the shaft, but maintaining the sections in rotatable driving relation to each other, of a governing device therefor comprising a permanently fixed block through which the longitudinal movable section of

the shaft extends with freedom of rotation; a diametrically opposed block slidably mounted on the said shaft section, adjustable means on the said shaft section for limiting the sliding movement of the said last named block, a spring tension device interposed between the confronting faces of said blocks, said device being normally maintained under tension when a normal drive is imparted to the propeller shaft, but capable of expanding to slide said slidably mounted block 45 and the driven section of the propeller shaft when the thrust incident to the normal drive of the propeller shaft is relieved, and means connected to said slidably mounted block 50 adapted to effect a throttling down of the 55 engine.

2. The combination of a propeller shaft divided by a coupling capable of permitting longitudinal movement of one of the shaft sections but maintaining the sections in rotatable driving relation to each other, of a governing device comprising a pair of opposed blocks spaced apart on the longitudinal movable section of the shaft, a tension device between said blocks being one of said 60 blocks capable of longitudinal movement relative to the other, a stop fixed to and adjustable on the shaft for limiting the sliding movement of said slidably mounted block; whereby expansion of the tension device may impart a longitudinal movement to the shaft section when the forward thrust incident to the drive of the propeller is relieved, bearings between the slideable block and the stop, and a governing control between the driving means for the propeller shaft and said longitudinal movable block. 65 70 75
